Primary Examiner — Susan Bennett Hattan*Assistant Examiner* — Omeed Agilee(74) Attorney, Agent, or Firm — Polson Intellectual Property Law, PC; Margaret Polson; Christopher Sylvain(57) CLAIM

The ornamental design for a nut milk maker, as shown and described.

DESCRIPTION

FIG. 1 is a front perspective view of a nut milk maker.

FIG. 2 is a front side elevation view of FIG. 1.

FIG. 3 is a back side elevation view of FIG. 1.

FIG. 4 is a left side elevation view of FIG. 1.

FIG. 5 is a right side elevation view of FIG. 1.

FIG. 6 is a top plan view of FIG. 1; and,

FIG. 7 is a bottom plan view of FIG. 1.

The dash lines in the drawings depict portions of the nut milk maker that form no part of the claimed design. The dot dash dot broken lines depict the boundaries of the claim and form no part thereof.
